CLAIM

The ornamental design for a computer keyboard, as shown and described.

DESCRIPTION

FIG. 1 is a top perspective view of the computer keyboard; FIG. 2 is a bottom perspective view of the computer keyboard;

FIG. 3 is a front-side view of the computer keyboard;

FIG. 4 is a rear-side view of the computer keyboard;

FIG. 5 is a left-side plan view of the computer keyboard;

FIG. 6 is a right-side plan view of the computer keyboard;

FIG. 7 is a top plan view of the computer keyboard; and,

FIG. 8 is a bottom plan view of the computer keyboard. The broken lines in FIGS. 1-8 depict portions of the computer keyboard that form no part of the claimed design.

1 Claim, 8 Drawing Sheets
